UNITED STATES PATENT OFFICE.

ARTHUR L. CANFIELD AND BYRON E. VAN AUKEN, OF CHICAGO, ILLINOIS.

RADIATOR RETURN-TRAP.

No. 890,555.

Specification of Letters Patent.

Patented June 9, 1903.

Application filed March 22, 1902. Serial No. 99,448.

To all whom it may concern:

Be it known that we, ARTHUR L. CANFIELD and BYRON E. VAN AUKEN, of Chicago, in the county of Cook and State of Illinois, have invented certain new and useful Improvements in Radiator Return-Traps; and we do hereby declare that the following is a full, clear, and exact description thereof, reference being had to the accompanying drawings, and to the letters of reference marked thereon, which form a part of this specification.

This invention relates to what may be styled a radiator return trap.

It has for its object the removal of the water of condensation and air from a steam radiator or any other receptacle where steam condenses.

The invention consists in the devices and combination of devices herein shown and described, and which will be more particularly pointed out in the appended claims.

In the drawings:—Figure 1 is a central, vertical, sectional view of a trap embodying our improvement. Fig. 2 is a similar view taken upon line 2—2 of Fig. 1. Fig. 3 is a transverse, horizontal sectional view taken upon the line 3—3 of Fig. 1. Fig. 4 is a similar view taken upon the line 4—4 of Fig. 1. Fig. 5 is a partial sectional view with the weir omitted.

The letter A represents the trap as a whole, the interior of which, together with the cap A¹, constitutes a float chamber a. At the lower end thereof and projecting laterally therefrom is a tubular extension B, exteriorly screw-threaded at b, so that a connection may be made with a steam radiator or other steam receptacle. The passage b¹ therein leads to a water chamber b² or pocket opening into the lower end of the float chamber and into which dips a weir a¹.

C is a float.

a² are guide lugs upon the interior of the shell A for guiding the float C. The lower end of the float C is provided with a valve c adapted to open or close upon a valve seat a³ which in this instance consists of a screw-threaded nut provided with a central vertically arranged discharge aperture a⁴. The discharge aperture a⁴ communicates with the discharge passage b³ of the trap constituting the bore of a branch B¹, the latter being interiorly screw-threaded, as shown, whereby connection may be made with any suitable discharge pipe.

D is an air discharge chamber communicating at its upper end with the float chamber a by means of a port d, formed in a screw-threaded nipple extending through the wall of the float chamber, and communicating at its lower end with the passage b³ by means of a passageway d¹. The upper end of the air chamber D is closed by a screw plug or cap d², and a suitable opening in its side opposite the passageway d is similarly closed by a screw plug or cap d³. Within the chamber D is an expansion valve device D¹ comprising two thermostatic members, the upper end of one member being secured, as shown, to the wall of the trap by the screw-threaded nipple in which is formed the port d, and the upper end of the other member being provided with a closure d⁴ adapted to close the port d when the thermostatically controlled device operates in one direction. The lower ends of the two thermostatic members of the valve device D¹ are secured together in any suitable manner, as for example, by a rivet d⁵.

The wall of the trap separating the pocket b² from the outlet passage b³ is provided with a by-pass e which is normally closed by a conical valve e¹ carried by a stem E. This stem E is screw-threaded at e² whereby it may be secured to the interior of a lateral extension B² of the trap. A suitable cap or plug B³ having screw-threaded connection with the outer end of the extension B², confines the packing b⁴ to prevent leakage, while the outer end of the plug E is provided with suitable means for turning the plug, as for example, by the nut e⁵.

Instead of the weir a¹ the wall of the passage b¹ may be formed to constitute a weir a⁵, as shown in Fig. 5, which serves the same purpose as the said weir a¹ illustrated in Fig. 1.

Steam being admitted to the radiator, the pressure of the steam drives the air from the radiator and float chamber through the thermostatically controlled air valve, which at this time is open, and when the air in said chamber is displaced sufficiently to permit the steam to impinge against the thermostatic bars D¹, carrying the air valve closure, said closure is moved toward its seat to close or partially close said valve. In practice, the thermostatically controlled air valve is adjusted to close entirely, only momentarily, but said valve, for the greater portion of the time, remains in a state of unstable equi-

librium, neither fully closed nor fully opened, so that for the greater part of the time, there is a slight leakage of air and vapor past the air valve. This is a common condition and 5 operation of valves of this character, and is not herein illustrated.

The water of condensation, which is discharged from the radiator, with which the trap is connected, with a limited volume of 10 air and steam or vapor, is directed through the inlet branch B of the trap to the pocket b^2 at the inner end thereof, and from thence enters the lower end of the float chamber. The condensation of steam or vapor which 15 thus enters the float chamber, together with the effect of the slight leakage of air past the air valve, creates such a difference of pressures between the radiator and the float chamber that the water is forced upwardly into 20 the float chamber until it rises to or above the line of flotation of the float, whereupon the float is elevated, thereby opening the water valve and permitting the water to escape from the float chamber into the outlet 25 branch or pipe B¹, partially emptying the float chambers and sweeping some of the water out of the pocket b^2 . When the water is thus emptied from the float chamber to a point below the line of flotation, the float de- 30 scends by gravity and closes the water outlet valve. When the upper part of the float chamber becomes filled with air and the body of air becomes cooled, said thermostatically controlled air valve opens to permit air to be 35 driven more freely therefrom by the pressure of steam in the radiator, and when steam again reaches the thermostatic bars the air valve is again closed or partially closed.

It will be understood that the adjustment 40 of the air valve is such that it does not often fully open during the operation of the trap to permit the air and vapor to escape freely from the float chamber to the return pipe, but that the valve, for the greater part of the 45 time, remains in a position to produce what is in effect a contracted vein. The variations of the temperature in the trap, however, causes the valve to vary in its opening and closing, and sometimes the air valve will be 50 entirely closed, while at others it will be fully opened.

By reason of the presence of the weir at the inner end of the inlet passage or branch of the trap which is submerged in the water 55 contained in said pocket or chamber b^2 and in the lower end of the float chamber, whereby the escape of any considerable amount of steam past the weir is prevented, said weir and pocket constitutes a trap located be- 60 tween the radiator and float chamber. While therefore, the slight leakage of air past the air valve and the condensation of steam in the float chamber establishes and maintains such difference of pressures between the radi- 65 ator and the float chamber as will cause the

water of condensation and air to pass upwardly into the float chamber and cause the float to rise, yet the presence of the weir prevents the escape of any considerable amount of steam through the float chamber and the 70 consequent wasting of such steam at the time the valve is thus opened. The thermostatically controlled air valve co-acts with the weir to produce the result referred to, and at the same time permits the escape of air from 75 the radiator and from the upper part of the float chamber when the body of air in the upper part of the float chamber becomes sufficiently cooled.

The presence of the valve e^1 between the 80 outlet side of the trap and the chamber or pocket b^2 enables the latter and the float chamber to be drained of the water which is not sufficient to lift the float, when the system in which the trap is embodied is out of operation 85 and thereby prevents the water from freezing in the trap. The entire removal of said valve e^1 and its stem E enables the chamber or pocket b^2 to be cleaned out without the necessity of removing the trap as a whole. 90

It will be noted that the heating system discharges through a valve controlled conduit, the valve of which is governed by a float that is actuated by water displaced from a seal located between the heating system 95 and the valve, by reason of the differential pressures on the opposite sides of said seal. Said conduit, in the present instance, comprises the lower part of the float chamber and its discharge passage, the pocket b^2 and the 100 part b by which communication is had with the heating system. It will be obvious, however, that the said parts of the conduit may be variously arranged with respect to each other without departing from the spirit of 105 the invention.

In the operation of a heating system equipped with a trap made as hereinbefore set forth, water of condensation from the system under some conditions of operation is forced 110 gradually into the float chamber of the trap, in which case the float is raised or lifted by flotation alone, while under other conditions of operation, a small or large quantity of water will be forced into the float chamber 115 at a comparatively high velocity and will tend to find its way to the upper part of the float chamber through the space between the float and its surrounding wall; it being, of course, understood that in all cases the 120 greater pressure on the radiator side of the liquid seal produces the influx of water to the float chamber and the upward movement of the water in the float chamber constitutes the medium through which the float is lifted. 125 While, in the form of trap shown in the accompanying drawings, the space between the float and the surrounding wall of the float chamber is sufficiently large to permit perfectly free vertical movement of the float, 130

yet such space is relatively small in proportion to the full horizontal area of the float chamber and as a consequence, when a volume of water enters the lower end of the 5 float chamber rapidly or with considerable velocity, a lifting effect is produced upon the float, other than that due to flotation alone, because the comparatively restricted space afforded for the upward flow or movement of 10 water within the float chamber necessarily results in such upward flow or movement being retarded to a greater or less extent, with the result that upward pressure is exerted on the float to a greater or less degree depending 15 upon the quantity of water admitted at one time and its velocity. Such upward pressure, when exerted to any degree, aids or augments the effect of flotation in giving upward movement to the float and effecting 20 the opening of the valve. To the extent to which upward pressure is exerted on the float by the rapid influx of a small quantity of water to the float chamber, or the more gradual entrance to the float chamber of a 25 comparatively large volume of water, or the rapid entrance thereto of a large volume of water, in a trap made as illustrated in the accompanying drawings, (in which the water of condensation enters the bottom of the 30 float chamber and the float is made of such dimensions horizontally as to occupy a greater part of the horizontal area of the said float chamber) the float acts as a piston or motor member to aid the effect of flotation 35 in lifting the float and opening the valve and an advantage in operation results in the way of promptness and certainty of action under relatively small differential pressure at opposite sides of the water seal.

40 We claim as our invention:

1. Valve mechanism for discharging air and water of condensation from steam heating systems by differential pressure, comprising a float chamber, a liquid discharge passage communicating therewith, a float for governing said discharge passage, a conduit adapted to provide communication between a radiator and said float chamber, a liquid seal arranged to be sealed by the 45 accumulation of water of condensation in said conduit, thereby increasing the differential pressure on opposite sides of said liquid seal, whereby a portion of the accumulated water of condensation is forced into 50 said float chamber, an air-discharge passage arranged to discharge the air after it has passed said liquid seal, said air discharge passage communicating with the liquid discharge passage beyond the float chamber, 55 and automatic means for restricting the flow of steam through said air discharge passage.

2. Valve mechanism for discharging air and water of condensation from steam heating systems by differential pressure, comprising a float chamber, a liquid discharge 60

passage communicating therewith, a float in said float chamber, a valve rigidly attached to and moving with said float for controlling said discharge passage, a conduit adapted to provide communication between a radiator 70 and said float chamber, a liquid seal arranged to be sealed by the accumulation of water of condensation in said conduit, thereby increasing the differential pressure on opposite sides of the liquid seal, whereby a portion of the accumulated water of condensation is forced into said float chamber, and an air discharge passage arranged to discharge the air after it has passed said liquid seal, said air discharge passage communicating with 75 the liquid discharge passage beyond the float chamber, and automatic means for restricting the flow of steam from said air discharge passage.

3. Valve mechanism for discharging air 80 and water of condensation from steam heating systems by differential pressure, comprising a float chamber, a liquid discharge passage communicating therewith, a float for governing said discharge passage, a conduit adapted to provide communication between a radiator and said float chamber, a liquid seal arranged to be sealed by the accumulation of water of condensation in said 85 conduit, thereby increasing the differential pressure on opposite sides of the said liquid seal, whereby a portion of the accumulated water of condensation is forced into said float chamber, and an automatically controlled air discharge passage arranged to discharge the air after it has passed said liquid seal, said air discharge passage communicating with the liquid discharge passage beyond 90 the float chamber.

4. Valve mechanism for discharging air 95 and water of condensation from steam heating systems by differential pressure, comprising a float chamber, a liquid discharge passage communicating therewith, a conduit adapted to provide communication between 100 a radiator and the liquid float chamber, a float in said float chamber for governing said discharge passage, a weir in said conduit having its lower edge substantially below the line of flotation of the float and forming a 105 liquid seal arranged to be sealed by the accumulation of water of condensation in said conduit, thereby increasing the differential pressure on opposite sides of the liquid seal, whereby a portion of the accumulated water 110 of condensation is forced into said float chamber, and an automatically controlled air discharge passage located beyond the float chamber and arranged to discharge the air after it has passed said liquid seal.

5. Valve mechanism for discharging air and water of condensation from steam heating systems by differential pressure, comprising a float chamber, a liquid discharge passage communicating therewith, a float for govern- 115

ing said discharge passage, a conduit adapted to provide communication between a radiator and said float chamber, a liquid seal arranged to be sealed by the accumulation of 5 water of condensation in said conduit, thereby increasing the differential pressure on opposite sides of the liquid seal, whereby a portion of the accumulated water of condensation is forced into said float chamber, and 10 a thermostatically controlled air discharge passage located beyond the float chamber and arranged to discharge the air after it has passed said liquid seal.

6. A steam trap comprising a shell having 15 a float chamber and provided with an inlet passage which opens into the lower end of the chamber, a pocket in said inlet passage for the collection of water of condensation, a float in said chamber, a weir depending into 20 said pocket, having its lower edge substantially below the line of flotation of the float, an outlet passage leading from said float chamber, a valve actuated directly by the float for controlling said outlet passage, and 25 an air discharge passage located beyond and leading from the float chamber above the level of the water required therein to lift the float.

7. A steam trap comprising a shell having 30 a float chamber provided with an inlet passage which opens into the lower end of said chamber and with an outlet passage leading from said chamber, a float in said chamber, a valve actuated directly by the float from controlling 35 said outlet passage, a pocket in the inlet passage for the collection of water of condensation to form a liquid seal, a weir depending into said pocket, and a passage adapted for the discharge of air after it has 40 passed said liquid seal, said air passage leading from the float chamber above the level of the water therein to lift the float and communicating with the outlet passage beyond the float chamber.

45 8. A steam trap comprising a shell having a float chamber and provided with an inlet passage which opens into the lower end of the chamber, a pocket in said inlet passage for the collection of water of condensation, a float in said chamber, a weir depending into 50 said pocket, having its lower edge substantially below the line of flotation of the float, an outlet passage leading from said float chamber, a valve actuated by said float for controlling 55 said outlet passage, and a thermostatically controlled air discharge passage located beyond and leading from the upper end of said float chamber and discharging outside of the trap.

60 9. A steam trap comprising a shell having a float chamber and provided with an inlet passage which opens into the lower end of the float chamber, a pocket in said inlet passage, a discharge passage leading from said float 65 chamber, a float in said chamber, a weir at

the inner end of said inlet passage depending into said pocket and located with its lower edge substantially below the line of flotation of the float, a valve actuated directly by said float for controlling said outlet passage of the 70 float chamber, and a thermostatically controlled air discharge passage located substantially above the line of flotation of the float leading from the upper end of the float chamber and discharging at its lower end 75 into the float chamber outlet passage.

10. A steam trap comprising a shell having a float chamber and provided with an inlet passage which opens into the lower end of the float chamber, a pocket in said inlet passage, 80 a discharge passage leading from said float chamber, a float in said chamber, a weir at the inner end of said inlet passage depending to said pocket and located with its lower edge substantially below the line of flotation of the float, a valve controlled by the float for closing the discharge passage of the float chamber, a thermostatically controlled air discharge passage leading from the upper end of the float chamber and discharging at its lower end into the float chamber outlet passage, and a valved by-pass connecting 85 said pocket at the inner end of the inlet passage with the outlet passage of the float chamber. 95

11. A trap comprising a shell having a float chamber and provided with an inlet passage, which opens into the lower end of said chamber, a float in said chamber, a weir at the inner end of said passage, an outlet passage 100 leading from said float chamber, a valve actuated directly by said float for controlling said outlet passage, and an automatically controlled air discharge passage leading from the upper end of said float chamber, and discharging outside of the trap. 105

12. Valve mechanism for discharging air and water of condensation from steam heating systems by differential pressure, comprising a float chamber, a liquid discharge 110 passage communicating therewith, a float for governing said discharge passage which occupies a greater part of the horizontal area of said float chamber, a conduit adapted to provide communication between the said 115 radiator and the lower part of said float chamber below the line of flotation of the float therein, a liquid seal arranged to be sealed by the accumulation of water of condensation in said conduit, thereby increasing 120 the differential pressure on opposite sides of the liquid seal, whereby a portion of the accumulated water of condensation is forced into said float chamber and acts to lift the float both by flotation and by the upward pressure 125 on the float due to its velocity, and an air discharge passage leading from the float chamber above the line of flotation and arranged to discharge the air after it has passed said liquid seal. 130

13. A steam trap comprising a shell having a float chamber and provided with an inlet passage which opens into the lower end of the said chamber below the line of flotation 5 of the float therein, a pocket in said inlet passage for the collection of water of condensation, a float in said chamber occupying the principal part of the horizontal area thereof, a weir depending into said pocket and having 10 its lower edge substantially below the line of flotation of the float, an outlet passage leading from said float chamber, a valve actuated directly by said float for controlling said out-

let passage, and an air discharge passage leading from the upper end of said float 15 chamber and discharging outside of the trap.

In testimony, that we claim the foregoing as our invention we affix our signatures in presence of two witnesses, this 20th day of March A. D. 1902.
